(57) CLAIM

The ornamental design for a display frame, as shown and described.

DESCRIPTION

FIG. 1 is a rear, bottom perspective view of a display frame, showing my new design;

FIG. 2 is a front, top perspective view thereof;

FIG. 3 is a rear elevational view thereof;

FIG. 4 is a front elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines show portions of the display frame that form no part of the claimed design.
